UNITED STATES PATENT OFFICE.

EDWIN W. WEBB, OF CHICAGO, ILLINOIS, ASSIGNOR TO STANDARD CAR TRUCK COMPANY, OF CHICAGO, ILLINOIS, A CORPORATION OF NEW JERSEY.

SIDE BEARING AND SUPPORTING-ARCH FOR CAR-TRUCKS.

1,149,234.

Specification of Letters Patent. Patented Aug. 10, 1915.

Application filed May 12, 1915. Serial No. 27,582.

To all whom it may concern:

Be it known that I, EDWIN W. WEBB, a citizen of the United States, residing at Chicago, in the county of Cook and State of Illinois, have invented certain new and useful Improvements in Side Bearings and Supporting-Arches for Car-Trucks; and I do hereby declare the following to be a full, clear, and exact description of the invention, such as will enable others skilled in the art to which it appertains to make and use the same.

My invention relates to six-wheeled car trucks and is directed to the provision of an improved side bearing arch and side bearing for trucks of this character.

Generally stated, the invention consists of the novel devices and combinations of devices hereinafter described and defined in the claims.

In the accompanying drawings which illustrate the invention, like characters indicate like parts throughout the several views.

Referring to the drawings: Figure 1 is a plan view showing a six-wheeled car truck, some parts being broken away; Fig. 2 is a side elevation of the parts shown in Fig. 1; Fig. 3 is an enlarged elevation with some parts sectioned, showing the central portion of one of the side bearing arches and one of the improved side bearings applied thereto; and Fig. 4 is a vertical section, the right end portion thereof being in section on the line x^4-x^4 , and the left end part being sectioned on the line $y-y$ on Fig. 3.

Of the parts of the truck, the numeral 1 indicates the wheels, 2 the axles, 3 the truck frame, 4 the equalizers, and 5 the spring-supported truck bolsters, all of which parts are, or may be assumed to be of standard well known construction.

The side bearing arch bars 6 are cast structures (preferably cast steel) and at their central portions, they are widened and formed with pockets or mortises 7, (preferably open in the bottom so that dust, dirt or water cannot accumulate within the same), to receive the side bearing rollers 8. These side bearing rollers are preferably arranged in pairs, that is, two for each arch bar and they are journaled on pins 9 passed through holes in the side walls of the pocket 7. The rollers are set so that their upper

portions project considerably above the upper surfaces of the arch bars.

Cover plates 10 which have openings through which the upper portions of the rollers project, are seated on the tops of the arch bars and close the tops of the pockets 7, and they are provided with down-turned side flanges that overlap more or less, the ends of the pins 9, and thus serve to hold the said pins against endwise or axial displacement. The cover plates themselves are held in position by nut-equipped bolts 11 passed through the central portions of the side flanges thereof, and through the walls of the pockets 7 midway between the two rollers. The cover plates above described are preferably made of malleable iron, but may be made of pressed steel or otherwise formed.

The ends of the arch bars 6 rest upon the ends of the truck bolster 5 and are rigidly secured thereto by bolts or other suitable devices; and when they are thus applied, the side bearings are supported in proper position for engagement with the customary cooperating bearing plates on the car body.

What I claim is:

1. In a six-wheeled car truck, side bearing arch bars provided at their intermediate portions with pockets and with side bearing rollers journaled in said pockets.

2. In a six-wheeled car truck, side bearing arch bars provided at their intermediate portions with pockets and with side bearing rollers journaled in said pockets, the said pockets having open bottoms.

3. A side bearing arch bar for car trucks, provided at its intermediate portion with a pocket, and with rollers journaled in said pocket.

4. A side bearing arch bar for car trucks, provided at its intermediate portion with a pocket, and with rollers journaled in said pockets, the bottom of said pockets being open.

5. A cast side bearing arch bar for six-wheeled trucks formed at its intermediate portion with a pocket, a pin extended through said pocket and the walls thereof, rollers journaled on said pin and a cover plate secured to said bar and having depending flanges overlapping the ends of said pin and holding the same against endwise displacement.

6. In a car truck, cast side bearing arch bars formed at their central portions with pockets, pins extended through said pockets in the walls thereof, rollers journaled on said pins, cover plates applied on said arch bars to close said pockets but having openings through which said rollers project and provided with depending flanges overlapping the ends of said pins and holding the same against endwise displacement.
7. In a car truck, cast side bearing arch bars formed at their central portions with pockets, pins extended through said pockets in the walls thereof, rollers journaled on said pins, cover plates applied on said arch

bars to close said pockets but having openings through which said rollers project and provided with depending flanges overlapping the ends of said pins and holding the same against endwise displacement, and nut-equipped bolts passed through the depending flanges of said cover plates and the walls of said pockets, at points between said rollers. 20

In testimony whereof I affix my signature 25
in presence of two witnesses.

EDWIN W. WEBB.
